UNITED STATES PATENT OFFICE

WALTER D. BANES, OF CHESTNUT HILL, PENNSYLVANIA, ASSIGNOR TO ISAAC L. SCHWARTZ, OF PHILADELPHIA, PENNSYLVANIA

FIRE EXTINGUISHER

Application filed March 4, 1931. Serial No. 519,924.

The invention relates to fire extinguishers, especially of the grenade type. The object is to provide improved grenade holding means, detent means for the holding means, 5 means for locking the detent means, means for causing the release of the locking means and of the detent means, so that the holding means will discharge the grenade, and means acting simultaneously for breaking the 10 grenade. Said locking and release causing mechanism and said breaking mechanism being normally restrained by fusible means adapted to become ineffective upon the occurrence of predetermined temperature.

15 Referring to the drawings which illustrate, merely by way of example, suitable means for effecting the invention—

Fig. 1 is a side elevation showing the device in normal position supporting the 20 grenade.

Fig. 2 is a front elevation of same.

Fig. 3 is a top plan view of same.

Fig. 4 is an elevation showing the positions of the parts after the discharge and 25 breaking of the grenade.

Fig. 5 is a horizontal section on the line 5, 5 of Figs. 1 and 2.

Fig. 6 is a perspective view of the fusible element.

30 Fig. 7 is a horizontal section of the bracket in an intermediate stage of production.

Similar numerals refer to similar parts throughout the several views.

The bracket 9 is made of sheet metal in 35 channeled formation. This bracket is first formed with the single channel 10 as shown in Fig. 7, the parts forming the side marginal walls 11 of the channel having been provided holes such as 12, properly positioned for the several pivot pins. After the 40 several pivot pins are inserted, with the elements supported thereby, the outer portions 13 of the plate are bent back parallel with the marginal walls 11 of the channel 10, as shown in Fig. 5, thus serving to cover the ends of the pivots and also maintaining the same in position.

Within the channel 10 of bracket 9 are 45 pivotally mounted a number of elements.

50 The loop element 14 has its free ends 15

bent outwardly into line with a common axis so that said ends may fit in suitable holes in the walls 11 of the bracket. The loop element 16 has its free ends 17 similarly bent to fit in suitable holes formed in the side 55 walls of the yoke 18, and as these elements 14 and 16 are made of spring wire their free ends may be pressed together for insertion or withdrawal with respect to their pivot holes. This arrangement makes it convenient to separate one or both of said elements from the bracket for packing. The loop or detent element 19 may be made of wire having its free ends 20 similarly bent to form pivots 60 for their respective holes in the side walls 11 of the bracket. The elements 18 and 21 are mounted on pivot pins 22 and 23 respectively, having their ends extending through the side walls 11 of the bracket 9. The outer walls 13 of the bracket overhang the ends of 65 these pins to cover same and prevent their displacement.

The yoke element 18 is provided with notches 24 for receiving portions of the loop element 16 and which cooperate with the 70 pivotal mounting of element 16 in said yoke for maintaining the element 16 in horizontal position when the yoke 18 is in latched relationship with detent 19. The yoke 18 is provided with shoulders 25, over which the detent 19 engages, when in normal latching position, with loop element 16 in horizontal 75 position for supporting the grenade 26.

The element 21 which is mounted on the pivot pin 23 is provided with a notch 26' 80 within which the cross-bar of detent 19 also rests when the parts are in the normal position as shown in Fig. 1. This element 21 is provided at its free end with the weighted head 27 and is connected, as at 28, with one 85 end of a spring 29, the other end of said spring being connected to the bracket as at 30.

When the element 21 is brought into the 90 vertical position as shown in Fig. 1, the detent 19 falls over the shoulders 25 of yoke 18, and holds the yoke in such position. When element 21 is brought into said vertical position as shown in Fig. 1, against the tension 95 of spring 29, it is held in such position against 100

said tension, by means of a fusible restraining element 31, as shown in Fig. 1. This element is shown in detail in Fig. 6, and comprises two members provided at one end with the hook formations 32. At the other end, one member is provided with two inclined fingers 33, while the other member is provided with the inclined finger 34 adapted to project between the fingers 33. In this position the fingers 10 are secured together by a fusible solder 35. This solder is associated with the upper sides of the fingers as well as with their adjacent edges, and is clearly visible, so that the condition of the fusible is always subject to inspection. The main bodies of the members are separated so as to straddle the arm of element 21 near the head 27, while the hook portions 32 engage the pivot pin 22.

20 *In operation*

When the parts are in position shown in Fig. 1, the ring or loop element 16 is held in horizontal grenade supporting position by means of its engagement with the yoke 18 25 both in the notches 24 and the pivot holes of the pivots 17. The yoke 18 is held in the position shown in Fig. 1 by the latch or detent 19 engaging over the shoulders 25 of the yoke. This detent 19 is locked in said 30 position against accidental disengagement from shoulders 25 by means of the notch 26' provided in element 21; this is to say, the upper margin of the notch 26' positively prevents the movement of yoke 18 so long as 35 element 21 is held in the position shown in Fig. 1.

As above stated the element 21 is held in the vertical position shown in Fig. 1, against the tension of spring 29 by the fusible device 31; which straddles the lower end of element 21 and has a hooked engagement with the pivot pin 22 which carries the yoke 18. The two parts of element 31 are normally held together by solder, or other heat affected 40 means, applied to the cooperating fingers 33 and 34, as at 35.

When this solder or other securing means is rendered ineffective by predetermined temperature conditions, the fingers 33 and 34 45 let go and separate, so that the element 21 moves, in response to the power exerted by spring 29, toward and finally to the position shown in Fig. 4. During this movement, the detent 19 is lifted out of engagement with shoulders 25 of yoke 18. The dotted lines in Fig. 4 indicate the original 50 relative position of detent latch 19 and shoulders 25 of the yoke. Upon the disengagement of the latch or detent 19 from shoulders 25, the yoke and the ring element 16 will fall to position shown in Fig. 4, thereby discharging the grenade. With the same 55 movement of element 21, the head 27 is brought into violent striking contact with

the lower side of the grenade to break or shatter the same.

While the element 16 will normally suffice to support the grenade, an additional element 14 is shown engaging with the upper 70 part of the grenade, preferably around the neck 36. This additional element is especially useful in cases where the bracket is subject to movement, as in marine use.

What I claim is:—

1. A holder and a detent normally cooperating therewith releasably to support a grenade, said detent being movable to release the holder to release the grenade, a detent actuator and fusible means for normally controlling the actuator.

2. A holder and a detent normally cooperating therewith releasably to support a grenade, said detent being movable to release the holder to release the grenade, a combined 25 detent actuator and detent locking means and fusible means for normally controlling the actuator and locking means.

3. A holder and a detent normally cooperating therewith releasably to support a grenade, said detent being movable to render the holder ineffective, an element having associated therewith means for actuating the detent and means for locking the detent against actuation and means for striking the 25 grenade, and a device, rendered ineffective upon the occurrence of predetermined temperature conditions, for normally controlling said element.

4. A pivotally supported element movable 100 about a horizontal axis for releasably holding a grenade, a detent for normally restraining its pivotal movement, a device for locking the detent in restraining position, and means for normally controlling said locking device, adapted upon predetermined temperature conditions to release the locking device to actuate the detent to release the holding element to discharge the grenade.

5. A pivotally supported element movable 105 about a horizontal axis for releasably holding a grenade, a detent for normally restraining its pivotal movement, a device for locking the detent in restraining position and also for moving the detent from restraining position to permit movement of the holding element to release the grenade and means for normally controlling said locking 110 and moving device, adapted to become ineffective upon predetermined temperature conditions.

6. A pivotally supported element movable 115 about a horizontal axis for releasably holding a grenade, a detent for normally restraining its pivotal movement, a device for locking the detent in restraining position, a spring for actuating said locking device and means for normally controlling said locking 120 device, adapted upon predetermined tem- 125

perature conditions to permit its spring actuation to disengage the detent to release the holding element to discharge the grenade.

7. A pivotally supported element movable about a horizontal axis for releasably holding a grenade, a detent for normally restraining its pivotal movement, a detent actuator and means, for normally controlling the said actuator adapted, upon predetermined temperature conditions to release the actuator whereby the detent is operated to permit the holding element to discharge the grenades.

8. A pivotally supported element movable about a horizontal axis for releasably holding a grenade, a detent for normally restraining its pivotal movement, a detent actuator and lock, and means for normally controlling the said actuator and lock adapted, upon predetermined temperature conditions, to release the actuator and lock whereby the detent is operated to permit the holding element to discharge the grenade.

9. A pivotally supported element movable about a horizontal axis for releasably holding a grenade, a detent for normally restraining its pivotal movement, a detent actuator and grenade breaker, and means for normally controlling the said actuator and grenade breaker adapted, upon predetermined temperature conditions, to release the actuator and breaker whereby the detent is operated to permit the holding element to discharge the grenade and the breaker to become effective.

10. A pivotally supported element movable about a horizontal axis for releasably holding a grenade, a detent for normally restraining its pivotal movement, means for locking the detent in restraining position, means for striking the grenade, and means for normally controlling said locking and striking means adapted, upon predetermined temperature conditions to release the locking and striking means whereby the detent is permitted to release the holding element to discharge the grenade and the striking means becomes effective.

11. A pivotally supported element movable about a horizontal axis for releasably holding a grenade, a detent for normally restraining its pivotal movement, means for locking the detent in restraining position, for actuating the detent and for striking the grenade, and means for normally controlling said detent locking and actuating means and said grenade striking means adapted, upon predetermined temperature conditions, to release said locking, actuating and striking means, whereby the grenade is discharged and broken.

60 12. A pivotally supported element movable about a horizontal axis for releasably holding a grenade, a detent for normally restraining its pivotal movement, a spring actuated device for locking the detent in restraining position for moving the detent out

of restraining position, and for striking the grenade, and fusible means for normally restraining said device adapted, upon predetermined temperature conditions to permit the actuation of said device whereby the grenade is discharged and broken.

13. A holder and a detent normally cooperating therewith to releasably support a grenade, the detent movable to release the holder to release the grenade, a detent actuator and fusible means for normally controlling the actuator, said fusible means including a securing solder so placed as to be clearly visible when the device is in operative position.

14. A holder and a detent normally cooperating therewith to releasably support a grenade, the detent movable to release the holder to release the grenade, a detent actuator and fusible means for normally controlling the actuator, said fusible means including cooperating elements having adjacent parts secured by a fusible solder so placed as to be clearly visible when the device is in operative position.
